ALARM BOX OR THE LIKE

Charles T. Waltman, Chicago, Ill., assignor to Faraday
Inc., Cincinnati, Ohio, a corporation of Ohio

Filed Apr. 10, 1961, Ser. No. 64,673

Term of patent 14 years

(Cl. D72—1)

FIG-2-

FIG. 1 is a perspective view of an alarm box showing my design; and

FIG. 2 is a perspective view thereof as seen from the left side of FIG. 1.

The dominant features of my design reside in the portions shown in full lines. The upper panel is shaded in the drawing to show contrast.

The rear is flat and substantially plain.

I claim:

The ornamental design for an alarm box or the like, substantially as shown and described.
